UNITED STATES PATENT OFFICE

171,515

TABLET DISPENSER

Kenneth D. Olsen, Madison, N. J.

Application March 24, 1953, Serial No. 24,191

Term of patent 14 years

(Cl. D58—12)

To all whom it may concern:

Be it known that I, Kenneth D. Olsen, have invented a new, original, and ornamental Design for a Tablet Dispenser, of which the following is a specification, reference being had to the accompanying drawing, forming a part hereof.

Fig. 1 is a front elevation of a tablet dispenser, showing my new design;

Fig. 2 is an end elevation thereof; and
Fig. 3 is a left side elevation thereof.

I claim:

The ornamental design for a tablet dispenser, as shown.

KENNETH D. OLSEN.
